Term of patent 14 years

(Cl. D34—5)

FIG.1

FIG.2

FIG. 1 is a plan view of a game board showing my new design; and

FIG. 2 is a cross-sectional view taken through line 2—2 of FIG. 1.

The characteristic feature of my design resides in an octagonal game board surrounded by a raised rail, said game board having a circular raised portion in the center thereof with opposed keystone formations between said circular area and the raised rail, said central portion having three circular depressions along its medial line, said

central portion and said opposed keystones being on the same plane.

I claim:

The ornamental design for a game board, substantially as shown and described.
